Primary Examiner—Robert M. Spear(57) **CLAIM**

The ornamental design for a sun visor "for sale" sign, as shown and described.

DESCRIPTION

FIG. 1 is a front elevational view of a sun visor "for sale" sign, showing my new design;

FIG. 2 is a rear elevational view thereof; and,

FIG. 3 is a front perspective view thereof, shown in a folded configuration of use.

This design related to auto, truck, boat and other vehicle sales. The broken lines in FIG. 2 are cut line indicia and form part of the claimed design.
